UNITED STATES PATENT OFFICE.

JOHN WILLIAM ESSER, OF GRAVELLY HILL, BIRMINGHAM, ENGLAND.

BREECH-LOADING SMALL-ARMS.

No. 853,073.

Specification of Letters Patent.

Patented May 7, 1907.

Application filed December 2, 1905. Serial No. 290,001.

To all whom it may concern:

Be it known that I, JOHN WILLIAM ESSER, a citizen of the United States of America, residing at 82 Fenthams road, Gravelly Hill, 5 Birmingham, in the county of Warwick, England, have invented certain new and useful Improvements in Breech-Loading Small-Arms; and I do hereby declare the following to be a full, clear, and exact description of 10 the invention, such as will enable others skilled in the art to which it appertains to make and use the same.

This invention relates to breech loading small arms, and refers more particularly to the 15 class of rifle or other small arm provided with a breech bolt connected with, and moved by a slide operated by the left hand, such bolt being made in two parts, whereof the back part, carrying the firing pin, slides in suitable 20 guides, and the forward part telescopes into the before-mentioned back part, and has a motion of rotation communicated to it, when the back part is pushed over it, by means of screw threads formed on such parts and in 25 engagement with one another, the locking and unlocking of such forward part of the breech bolt in the breech being thus effected.

The chief objects of the invention are to enable the breech bolt of a small arm of the 30 before-mentioned class to be very rapidly manipulated without removing the arm from the shoulder, so as to increase the rapidity of firing. At the same time the rods and other mechanism connecting the hand slide with 35 the breech bolt are so arranged and located that they are not exposed to the likelihood of injury or damage in case of the arm being dropped or receiving a blow. The trigger mechanism is so constructed and arranged, 40 that it affords absolute security against firing before the breech bolt has been properly locked in position; a device being also furnished for locking the whole mechanism, when necessary, so that the arm cannot be 45 discharged without unlocking such device. Means are further provided for stopping the supply of cartridges from a magazine, when required, whereby the arm can be used as a single shot rifle or gun.

50 According to my invention I connect to, or form with the back portion of the breech bolt, two rods which slide in grooves in the stock and the sides of the breech bolt receiver, which rods are connected directly to a plate, 55 preferably of the same shape as the under portion of the rifle, and capable of sliding

freely backward and forward, or they may be connected to a slide sliding in a slot formed in the stock of the rifle beneath the barrel, which slide is, in turn, connected to the sliding plate. 60

The trigger mechanism is of a known type—in which the sear helps to lock the breech bolt in position when the firing pin is released, and as long as the trigger itself is pressed, 65 while the sear is locked as soon as the breech bolt is released, and in which the trigger itself is pivoted directly to one end of the sear, the ejector being pivoted to the other end if found desirable—suitable constructional modifications being made in such known mechanism where desired to suit our particular small arm. 70

The locking device is of that type in which the firing pin is locked simultaneously with the breech bolt, and thus, in locking the 75 breech bolt, locks the sliding plate and other parts rigidly connected thereto. And in order that my said invention may be better understood I will now proceed to describe the same with reference to the drawings accompanying the specification, in which:— 80

Figure 1 is a longitudinal section of the mechanism of the rifle; Fig. 1^a is a longitudinal section through the barrel and partly broken away; Fig. 2 is an outside elevation 85 of the rifle with the breech bolt in position ready for firing; Fig. 2^a is an elevation of the forward portion of the gun with the sliding plate in its normal position; Fig. 3 is a similar view to Fig. 2, with the breech open; Fig. 90 3^a is a similar view to Fig. 2^a with the sliding plate removed; Fig. 4 shows a view of the clip containing the cartridges; Fig. 5 shows trigger mechanism; Figs. 6 and 7 show catch for lowering the cartridge clip or frame; Fig. 95 8 shows sectional elevation of Fig. 6; Fig. 9 shows outside elevation of breech bolt detached; Fig. 10 shows a section through line A. B., Fig. 9. Fig. 11 shows a section through the breech bolt receiver at line C. D. Fig. 12 100 shows a plan view of metal shoe for protecting the back of the breech. Fig. 13 shows a back end view of the breech receiver.

The same letters and numerals of reference are employed to denote the same parts in all 105 the views:—

a shows the breech bolt; *b* shows firing pin; *c* shows guides in which the bolt *a* slides. On each side of the breech bolt is fixed or formed a pin *d*, on each of which pins a rod *e* is fixed. 110 These rods slide in grooves *y* in the sides of the breech receiver (shown clearly at Fig. 11)

and to the opposite end of each of these rods is connected a sliding piece *f*, which slides freely backward and forward in the slot *g*. To the sliding piece *f* is connected a plate *h*, 5 of the same shape as the under portion of the rifle, which plate *h* is free to move backward and forward. The under portion of the breech bolt *a* is provided with a slot *k*, shown more clearly at Fig. 9.

10 *m* is a shoulder on the under portion of the breech bolt.

n is the sear rest.

15 *o* is the sear pivoted at *s* to the under part of the breech bolt receiver, and also at *p* to the trigger *q*.

20 *r* is the ejector working on a pin fixed in the sear at *s*. The tail portion of the ejector *r* is made springy and bears against the trigger at *t*. When the ejector is not connected 25 with the sear *o*, a guide pin is inserted in the hole *6* in the trigger.

25 *u* is the magazine provided with the usual spring mechanism for raising the cartridges. The cartridges are held in a clip or frame *v*, which is of the ordinary construction but provided with a slot *w*, for the purpose herein-after described.

30 *x* is a catch pivoted to the side of the magazine (see Fig. 8). This catch is provided for lowering the clip *v* as hereinafter described, and is shown drawn to a larger scale at Figs. 6, 7 and 8. It may be kept in its normal position by means of a suitable spring.

35 *1* is the catch to retain the clip *v* in position. To the side of the breech bolt *a*, is pivoted a safety catch *2*, which takes into slots *3* (Fig. 10) in the firing pin.

40 The action is as follows:—Supposing the rifle to be in the position shown at Fig. 3, the clip *v* containing the cartridges would be placed in the magazine *u* in the ordinary way. The plate *h* would then be gripped by the hand and pushed forward into the position shown at Fig. 2, and the mechanism would 45 then assume the position at Fig. 1, with a cartridge in the breech ready for firing. Unless the breech bolt is pushed completely home so that the point of the sear *o* rests behind the shoulder *m*, the rifle cannot be fired 50 either accidentally or otherwise, as the back of the sear *o* cannot be brought down far enough to allow the sear rest *n* to pass. The nose of the sear *o*, resting against the shoulder *m*, serves as additional security against 55 the breech bolt being forced or pulled back, so long as the trigger is held. On pulling the trigger, the back of the sear is drawn down from the sear rest *n*, thus releasing the firing pin. Upon drawing the plate *h* back again, 60 which, by means of the rods *e*, also pulls back the breech bolt, the cartridge case is extracted (by any suitable extractor) from the breech and brought back with the breech bolt and ejected when it comes in contact 65 with the nose of the ejector *r*. It will be seen

that the spring on the ejector *r* also serves to keep the trigger *q* and sear *o* in position. If it is required to lock the breech bolt and all the mechanism so that the rifle cannot be fired accidentally or otherwise, it is simply 70 necessary to press up the safety catch *2* by which action such catch will enter a slot *5* (shown at Fig. 13) in the bottom of the receiver, and also one of the slots *3* in the back part of the firing pin. When it is required to 75 put the magazine out of action and use the weapon as a single shot rifle or gun, it is necessary to press the catch *x* up, and this will cause the inner end *7* of such catch to enter the slot *w* in the clip *v* (see Fig. 8), and such 80 catch will press on the bottom of the slot *w* and force the clip *v* down so that the top cartridge will be clear of the breech bolt, and at the same time the catch will lock the clip *v* in the downward position. By pressing the 85 catch *x* down the clip will return to its normal position in the magazine. In the event of the cartridge missing fire, the firing pin may be again put in the firing position by drawing it back by means of the tail *8* without opening the breech.

90 By constructing rifles and other small arms as above described, the parts actuating the back portion of the breech bolt are entirely protected, and there is no possibility of 95 injury or damage to them in case of the arm being accidentally dropped or receiving a blow.

99 Although I have described this invention as applied to a military rifle, it is equally applicable to breech loading sporting and other guns and rifles, the magazine and clip being modified to suit the cartridges. It would thus not be necessary to use a double barrelled gun as two or more cartridges can be 105 fired in rapid succession.

What I claim and desire to secure by Letters Patent of the United States of America is:—

1. In a device of the character described, 110 the combination with the breech mechanism, a firing pin, a trigger, a sear pivotally connected to said trigger, and a cartridge ejector pivotally connected to said sear and provided with a spring tail portion adapted to 115 bear against said trigger for the purpose specified.

2. In a device of the character described, 120 the combination with the breech mechanism of a firing pin, a trigger, a sear pivoted at one end to said trigger and operating to lock said breech mechanism when said trigger is unlocked and to lock said trigger when said breech mechanism is unlocked, and a cartridge ejector pivotally connected to the 125 other end of said sear and provided with a spring tail portion adapted to bear against said trigger for the purpose specified.

3. In a device of the character described, 130 the combination with a breech mechanism,

- of a firing pin adapted to be reset upon the actuation of said mechanism, means for resetting said firing pin independent of said breech mechanism, a trigger, a sear pivotally connected to said trigger, and a cartridge ejector pivotally connected to said sear and provided with a spring tail portion adapted to bear against said trigger, substantially as described.

4. In a device of the character described, the combination with a breech mechanism, of a firing pin adapted to be reset upon the actuation of said mechanism, means for resetting said firing pin independent of said breech mechanism, a trigger, a sear pivotally connected at one end to said trigger and operating to lock said breech mechanism when said trigger is unlocked, and to lock said trigger when said breech mechanism is unlocked, and a cartridge ejector pivotally connected to the other end of said sear and provided with a spring tail portion adapted to bear against said trigger, substantially as described.

5. In a device of the character described, the combination with a two-part telescoping breech bolt normally locked within the gun, means for actuating said breech bolt, means for automatically releasing said breech bolt upon the actuation of the same, a firing pin operating within said breech bolt, a trigger, a sear pivotally connected to said trigger, and a cartridge ejector pivotally connected to said sear and provided with a spring tail portion adapted to bear against said trigger, substantially as described.

6. In a device of the character described, the combination with the breech mechanism, a firing pin, a trigger, a sear pivotally connected to said trigger, and a cartridge ejector pivotally connected to said sear and provided with a spring tail portion extending below said sear and bearing against said trigger, substantially as described.

7. In a device of the character described, the combination with a breech mechanism, of a firing pin adapted to be reset upon the actuation of said mechanism, means for resetting said firing pin independent of said breech mechanism, a trigger, a sear pivotally connected to said trigger, and a cartridge ejector provided with a spring tail portion extending below said sear and bearing against said trigger, substantially as described.

8. In a device of the character described, the combination with a two-part hollow telescoping breech bolt normally locked within the gun, means for actuating said breech bolt, means for automatically releasing said breech bolt upon the actuation of the same, a firing pin operating within said breech bolt, a trigger, a sear pivotally connected to said trigger, and a cartridge ejector pivotally connected to said sear and provided with a spring tail portion extending below said sear and bearing against said trigger, substantially as described.

9. In a device of the character described, the combination with a breech mechanism, of a magazine adapted to automatically feed cartridges to said breech, means for locking said magazine from action, a cartridge ejector arranged adjacent said breech mechanism and said magazine, a trigger, a sear pivotally connected at one end thereof to said sear, said ejector being pivotally connected to the other end of said sear and provided with a spring tail portion bearing against said trigger, substantially as described.

10. In a device of the character described, the combination with a two-part hollow, telescoping breech bolt and means for operating the same, of a magazine adapted to automatically feed cartridges to said breech upon the actuation of the same, means for locking said magazine from action, a cartridge ejector arranged adjacent said breech mechanism and said magazine, a trigger, a sear pivotally connected at one end thereof to said trigger, said ejector being pivotally connected to the other end of said sear and provided with a spring tail portion extending below said sear and bearing against said trigger, substantially as described.

In testimony whereof, I affix my signature, in presence of two witnesses.

JOHN WILLIAM ESSER.
